HAIR RETAINER

Crofton C. Holden, Leominster, Mass., assignor to
Tilton & Cook Co., Leominster, Mass., a corporation of Massachusetts

Application October 24, 1944, Serial No. 560,100

1 Claim. (Cl. 132—46)

The present invention relates to hair retainers. The object of the present invention is to provide a hair retainer which, without any clasps or other moving parts, may be easily engaged in the hair or removed therefrom by a simple twisting motion.

With this object in view, the retainer comprises a member, preferably molded of plastic material, having a series of spirally radiating spokes constructed and arranged to be inserted into the hair. As hereinafter described, the spokes are formed in a manner such that adjacent spokes are close to each other at an intermediate portion, while an open space is provided near the roots of the spokes for accommodation of the hair. By this means, a secure gripping action may be obtained.

The device may be used simply as a retainer, or may be provided with a suitable ornament.

In the accompanying drawing, Fig. 1 is a plan view of the retainer on an enlarged scale; Fig. 2 is an elevation of the retainer showing an ornament attached thereto; and Fig. 3 is an illustration showing attachment of the device to the hair.

The retainer comprises a disc-like member, preferably molded from a single piece of plastic and of slightly concave form, as shown in Fig. 2. The disc has a solid central portion 4, from which a number of spokes 6 radiate. As shown in Fig. 1, the spokes radiate spirally from the central portion 4, and as indicated in Fig. 2, they extend downwardly to give the concave form.

The shape of the spokes is important. As shown in Fig. 1, the root section 8 of each spoke (that is, the portion adjacent the disc 4) radiates outwardly at a relatively small angle from the radius. The outer portion 10 of each spoke is at

10 a considerably larger angle from the radius. Accordingly, two adjacent spokes come close together at the point 12 and leave a relatively large open space 14 between the outer ends of the spokes and another relatively large inner space 16 adjacent to the roots of the spokes. The spokes are preferably pointed at their ends for easy insertion into the hair.

15 The retainer is inserted into the hair by a relatively simple twisting motion with the concave side of the device towards the scalp. By virtue of this action, a number of strands of hair between the spokes at the outer end are caused to pass through the narrow opening 12 and are retained in the larger inner opening 16. Thus the device is secured in position, since the removal of the device requires sufficient contraction of the entrapped strands to pass through the narrow opening 12. The device may, however, be easily removed from the hair by a twisting motion in 20 a reverse direction from that required for insertion.

25 As shown in Fig. 2 in dot-and-dash lines, an ornament 18 may be cemented to the retainer. The device may be used, however, as a simple hair retainer without an ornament, if desired.

Having thus described my invention, I claim:

30 A hair retainer comprising a concave disc-like member having a central portion and spoke members radiating therefrom, each spoke having its outer portion at a greater angle from the radius than its inner portion, whereby adjacent spokes are close together at intermediate portions and are relatively further apart to provide open spaces near the roots of the spokes.
